UNITED STATES PATENT OFFICE.

ALFRED O. LEE, OF SALEM, ILLINOIS.

CABLE HOLDER.

Application filed August 28, 1922. Serial No. 584,925.

To all whom it may concern:

Be it known that I, ALFRED O. LEE, a citizen of the United States, residing at Salem, in the county of Marion and State of Illinois, have invented certain new and useful Improvements in Cable Holders, of which the following is a specification.

This invention relates to a cable holder and has for its principal object to provide a device of the above mentioned character which is adapted to be lowered into the casing of an oil well for the purpose of taking up the slack in the cable which is connected to the walking beam.

Another object of this invention is to provide a cable holder of the above mentioned character, which can be easily and readily placed in operation and furthermore which does not necessitate the use of a complicated structure for the purpose of taking up the slack in the cable which is being lowered into the oil well.

A still further object of the invention is to provide a cable holder of the above mentioned character, which is simple in its construction, inexpensive in its manufacture, strong and durable.

Other objects and advantages of this invention will become apparent during the course of the following description.

In the drawings forming a part of this specification and in which like numerals designate like parts throughout the same.

Figure 1 is a central vertical section of the invention, and

Figure 2 is a top plan view of the same.

In the drawings wherein for the purpose of illustration is shown the preferred embodiment of my invention, the numerals 1 and 2 designate two hollow semi-cylindrical sections comprising my cable holder or plug. These sections 1 and 2 are hingedly connected to each other by suitable hinge members 3 and are held in locked position by any suitable fastening means 4 as shown more clearly in Figure 2 of the drawings. The two hollow sections 1 and 2 are provided at their upper ends with a cover 5 and at their bottom ends with a cover 6 and formed in these covers are centrally disposed openings 7 and 8 respectively.

The purpose of these openings 7 and 8 is to allow a cable 9 which is being lowered into the oil casing to pass centrally through the plug. To further aid in centrally supporting the cable 9 in the plug I

provide suitable guide members 10 and 11. These guide members consist of slidable pulleys which are adapted to slide within the casings 12 and 13 which are mounted on the inner walls of the sections 1 and 2 respectively of the plug and to further aid in holding the pulleys 10 and 11 in engagement with the cable 9 I provide within the casings 12 and 13 spring elements 14 and 15 respectively. These spring elements will thereby cause the pulleys 10 and 11 to engage the cable at all times regardless of the movement of the cable in a sidewise direction. These guide members 10 and 11 are arranged on the top of the plug and also at the bottom thereof. However it is only necessary to describe one set of these as the other set is exactly the same.

Clamping members 16 and 17 are associated with the sections 1 and 2 of the plug in such a manner so as to be pivotally mounted on the inner walls of the sections 1 and 2 as at 18 and 19. These clamping members 16 and 17 are oppositely disposed with relation to each other and consist of diverging serrated jaws 20 and 21 for the purpose of enabling the clamping members to more easily and readily engage the cable line passing therebetween. Extending upwardly from the clamping members 16 and 17 and carried thereby are the lugs 22 and 23 and these lugs 22 and 23 are provided at their outer ends with pins 24 and 25 respectively. These pins 24 and 25 are adapted to work in the slotted ends 26 and 27 respectively of a cross bar 28 for a purpose hereinafter to be fully described.

These cross bars 28 extend across the clamping members 16 and 17 and within the two sections 1 and 2 of the plug in such a manner as to operate over the clamping members 16 and 17 simultaneously. The operating means consists of a rod 29 which is connected and carried by the cross bars 28 and extends upwardly within the plug and beyond the top portion 5 thereof. As there are two sets of these clamping members 16 and 17 arranged within the plug, one of the said sets being arranged in the top portion thereof and the other near the bottom, the cross bars 28 will necessarily have to be provided in one instance with a shorter rod 29 which enables the clamping members 16 and 17 to be arranged adjacent the upper end of the plug to be operated whereas the other set of clamping members

16 and 17 adjacent the lower end of the plug has a cross bar 28 provided with the rod 30 which extends upwardly through the plug and through the top side thereof so as to allow the operator to control the clamping members 16 and 17 adjacent the lower portion of the plug. These rods 29 and 30 have at their outwardly extending portions, handles for easily operating the same.

To further support the plug or cable holder within the oil well casing when in use, the sections 1 and 2 are provided with wedge members 31 and 32 respectively in their sides and near the center thereof for slidably engaging the walls of casing 33 wherein the plug 1 is placed. These wedge members 31 and 32 are controlled, by means of levers 34 and 35 respectively and these levers 34 and 35 extend upwardly in the sections 1 and 2 of the plug and beyond the top portions 5 thereof so that the same may be easily operated. To further support these rods 34 and 35 suitable guide means 36 and 37 is associated or carried by the inner walls of the sections 1 and 2 respectively.

In use when the cable upon one end of which is attached the operating or working tool, is lowered into the oil well casing, the sections 1 and 2 are uncoupled by means of releasing the hooks 4 and are adapted to enclose the cable in such a manner that the guide members 10 and 11 and the clamping members 16 and 17 will respectively engage the cable 9. After the same is in position the plug is then lowered into the casing a suitable distance so as to enable the operator to control the clamping members 16 and 17. The operator then operating the levers 34 and 35 causes the wedge members 31 and 32 to engage the casing 33 of the oil well and thereby securely hold the plug in the casing. As the table 9 is being lowered into the oil well casing the clamping members 16 and 17 will have their serrated jaws 20 and 21 at all times engaging the cable 9 and will have a tendency to grip the cable 9 in such a manner as to prevent the sudden and quick pull on the cable and furthermore will grip the cable tightly. The guide members 10 and 11 will have their pulleys engaging the cable 9 so as to allow the same to pass easily through the plug 1 without any danger of rubbing against the side walls of the apertured portion formed in the casing. Whenever it is necessary to release the clamping members 16 and 17 from engagement with the cable 9 so as to allow the cable 9 to be further let down within the oil well casing the operator pulls upwardly upon the rods 29 and 30 thereby causing the pins 24 and 25 carried by the up-standing lugs 22 and 23 on the clamping

means to slidably operate within the cross bar 28 which is connected to the rods 29 and 30 and further pull upwardly upon the clamping members 16 and 17 to disengage the clamping jaws 20 and 21 thereof from engagement with the cable 9. As each of these cross bars 28 is connected to one pair of the clamping members 16 and 17 the operation is easily facilitated and furthermore positive in its action.

It will thus be seen from the foregoing description, that an easy method and more useful manner has been described whereby in the lowering of a cable within the oil well casing any slack of the cable may be easily taken up and also hold the cable in any desired position.

It is to be understood that the form of my invention herewith shown and described is to be taken as the preferred embodiment of the same, and that various changes in the same size, and arrangement of parts may be resorted to without departing from the spirit of the invention or the scope of the subjoined claims.

Having thus described my invention what I claim as new and desire to secure by Letters Patent is:

1. A cable holder of the class described comprising a plug, a cable associated with the plug, a clamping member engaging the cable, means carried by the plug for releasing the clamping member from the cable and means for detachably connecting the plug with a well casing.

2. A cable holder of the class described comprising a plug, a cable associated therewith, means carried by the said plug for clamping the cable, and means mounted on the said plug for supporting the same within an oil well casing.

3. A cable holder of the class described comprising a plug, a cable associated with the plug, a clamping member carried by the plug and engaging the said cable, a guide member on the said plug for engagement with the cable, means for releasing the clamping member from the cable, supporting wedge members carried by the plug, and means for projecting the members beyond the periphery of the plug.

4. A cable holder of the class described comprising a plug, said plug consisting of a hollow central portion, a cable passing therethrough, a clamping member carried by the inner wall of said plug for engagement with the cable, a guide member slidably mounted in the plug and engaging the said cable, and means associated with the clamping member for releasing the same from engagement with the cable.

5. A cable holder of the class described comprising a plug, said plug consisting of two hollow sections, a cable passing centrally through the said plug, clamping

members pivotally mounted on the inner wall of the sections and oppositely disposed for clamping the cable, guide members slidably and operably mounted on the inner wall of the two hollow sections, and means associated with the clamping members for releasing the same from engagement with the cable.

6. A cable holder of the class described comprising a plug, said plug consisting of two hollow sections, a cable passing centrally through the said plug, clamping members pivotally mounted on the inner wall of the sections and oppositely disposed for clamping the cable, guide members slidably and operably mounted on the inner wall of the two hollow sections, means associated with the clamping members for releasing the same from engagement with the cable, and means mounted on the said plug for supporting the same within an oil well casing.

7. A cable holder of the class described

comprising a plug, said plug consisting of two hollow sections hingedly secured together, a cable passing centrally through the two hollow sections, clamping members pivotally mounted on the inner wall of the sections and operably disposed for clamping the cable, guide members slidably and oppositely mounted on the inner walls of the two hollow sections, spring elements associated with the guide members for keeping the guide members in engagement with the cable at all times, means associated with the clamping members while releasing the same from engagement with the cable, and wedge means supported on each side of the sections for supporting the plug within the casing of an oil well.

In testimony whereof I affix my signature in presence of two witnesses.

ALFRED O. LEE.
